ELECTROOPTICAL DARK TRACE PICTURE
TUBE

Gustave Levy and Walter Simbrat, East Orange,
N. J., assignors to National Union Radio Cor-
poration, Orange, N. J., a corporation of Dela-
ware

Application October 23, 1948, Serial No. 56,086

9 Claims. (Cl. 315—13)

1

This invention relates to electro-optical re-producing systems, and more particularly it relates to systems employing so-called "dark trace" tubes.

It has been known for some time that certain materials, such for example as normally transparent "ionic crystals," when impinged upon by a beam of electrons or cathode rays, develop localized opacity areas. Examples of such crystals are the halides of the alkaline metals or of the alkaline earth metals, and also certain salts of silver, for example silver bromide. For convenience, the expression "dark trace" tube is used herein as referring to a cathode-ray tube wherein the image-producing screen is composed, at least in part, of such ionic crystal material or materials. Likewise, for convenience, the expression "ionic crystal" refers to those crystals which have the property of developing localized opacity areas in response to impinging electrons or cathode-ray beams and includes those crystals containing positive and negative ionized or ionizable components which are held together mainly by electrostatic forces.

Accordingly, a principal object of this invention relates to an improved image-producing and erasing arrangement for "dark trace" cathode-ray tubes.

Another object is to provide a "dark trace" cathode-ray tube with a pair of electron guns, one of which produces a scanning beam of signal-modulated intensity, and the other of which produces an image-erasing beam of a higher intensity.

Another object is to provide an improved method and arrangement for erasing images on the screens of "dark trace" tubes by employing a combined electric field and electronic heating of the screen by means of a special cathode-ray beam.

A feature of the invention relates to an image tube of the "dark trace" type having an image-producing screen comprised of an extremely thin sheet of light transparent material such as glass, mica, or the like, on which the ionic crystal material is deposited. Cooperating with this screen are two electron guns, one of which produces the localized opacity image areas in response to received electric signals, and the other of which produces an intense cathode-ray beam for erasing the previously produced "dark trace" image.

Another feature relates to an image-reproducing tube of the "dark trace" type, wherein the image-producing screen consists of a light transparent thin sheet of backing material such as

2

glass, mica or the like, and having a light transparent coating of metal such as aluminum, and with the ionic crystal material sandwiched between the aluminum coating and the backing sheet. By means of a special high intensity cathode-ray beam, the previously produced "dark trace" image can be erased by the combined electronic heating of the backing sheet by the impinging cathode-ray beam and also by the electrostatic field created between the transparent aluminum coating and the said backing material.

Another feature relates to an image-producing tube of the "dark trace" type having an image screen comprised of a very thin plate or sheet of light transparent and electric insulating material such as glass, mica or the like, which carries a coating or layer of ionic crystals. The said mica sheet is chosen of sufficient thinness so that when it is bombarded by a high intensity cathode-ray beam, its temperature is raised to a point sufficient to effect erasure of the "dark trace" image.

A further feature relates to a cathode-ray tube having a pair of electron guns, one of which produces a signal-modulated cathode-ray beam for setting-up a "dark trace" image, and the other of which sets-up a high intensity cathode-ray beam to erase the previously set-up "dark trace" image. The image screen consists of a backing of light transparent material such as mica, glass or the like, having on its side facing both cathode-ray beams, a light transparent coating of metal such as aluminum. Sandwiched between the aluminum and the mica or glass plate is the layer of ionic crystals. In accordance with one feature of the invention, the aluminum coating is connected to the second anode of the cathode-ray tube gun system so that the cathode-ray beam from the erasing gun sets-up a relatively high potential gradient between the aluminum coating and the mica sheet. As a result, the "dark trace" image can be erased by the combined heating of the ionic crystals resulting from the high intensity bombardment of the mica plate and by the said high potential gradient between the aluminum coating and the said plate.

Another feature of the invention relates to an image-producing and erasing screen for "dark trace" cathode-ray tubes comprised of a backing sheet or plate of very thin light transparent material such as mica or glass, and a light transparent coating of metal such as aluminum, with a layer of ionic crystals sandwiched between the aluminum coating and backing plate. The alu-

minum layer is provided with a coating of secondary electron-emissive material so that when it is bombarded by a special erasing cathode-ray beam, it assumes a sufficient positive potential with respect to the ionic crystals to effect erasure of the previously recorded "dark trace" image therein.

A further feature relates to the novel organization, arrangement and relative location and proportioning of parts which cooperate to provide an improved image tube of the "dark trace" type.

Other features and advantages not particularly enumerated, will be apparent after a consideration of the following detailed descriptions and the appended claims.

In the drawing which shows one preferred embodiment,

Fig. 1 is a view, partly sectional, of an image-producing tube embodying features of the invention.

Fig. 2 is a magnified sectional view of part of the screen of Fig. 1.

Referring to the drawing, there is shown an evacuated enclosing envelope 1 having two diverging neck portions 2, 3, within which are respectively located the electron guns 4, 5. The neck portions communicate with a common chamber or body portion 6 of the tube which is closed off by the usual curved or flattened viewing end wall 7. The interior surface of the necks 1 and 3 and part of the body portion 6, is coated with a conductive material 8, such as "Aquadag," for purposes well-known in the cathode-ray tube art. A connection lug 9 is also provided, in the usual way, for making electrical contact with the coating 8.

The guns 4 and 5 may be of any construction well known in the cathode-ray tube art. Thus gun 4 may include an electron-emitting cathode 10, an apertured beam intensity control electrode 11, a first accelerating and beam-focussing anode 12, and a second or high potential accelerating and focussing anode 13. For the purpose of moving the focussed beam in the desired scanning trace or pattern, there may be provided any well-known beam deflecting arrangement comprising, for example, horizontal deflecting plates 14 and vertical deflecting plates 15. These plates are connected in the conventional manner to any well-known source of saw-tooth deflecting voltage 16 whereby the beam is recurrently deflected at the desired "line" scanning rate and "frame" scanning rate, in the manner well-known in the television scanning art.

The gun 5 may likewise comprise an electron-emitting cathode 17, an apertured beam intensity control electrode 18, and first and second accelerating and focussing anodes 19, 20. The electron gun 5 is also provided with a beam deflecting arrangement comprising, for example, horizontal deflector plates 21 and vertical deflector plates 22, for causing the beam from gun 5 to trace substantially the same pattern as that produced by gun 4. However, in order to produce a predetermined timed delay between the scanning motion of the two beams, the saw-tooth wave source 16 may be connected to the plates 21 and 22 through any well-known time delay network 23. With this arrangement, therefore, the trace of the beam from gun 5 follows the trace of the beam from gun 4 but at a predetermined time delay. As will be pointed out hereinbelow, it is not necessary that the two beams follow each other in phase displaced synchronism, pro-

viding the beam from gun 5 is rendered effective at a regular high frequency rate to erase the "dark trace" image.

Suitably mounted adjacent the tube end 7 is an image-producing screen comprising a thin plate or sheet 24 of a light transparent material such as mica or glass. In accordance with one feature of the invention, this sheet or plate is fabricated as thin as possible so as to have a minimum of heat capacity or heat inertia. For example, in the case of glass, it has been found that a thickness of .006 inch or less is preferable, and in the case of mica, a thickness of .003 inch or less is preferable. As shown in the drawing, the sheet 24 is mounted so as to intercept the beams from both of the guns, and it will be understood that both beams, or at least the beam from gun 4 is focussed in a minute scanning spot upon this sheet. Attached to the side of sheet 24, facing the guns, is a layer 25 of ionic crystals as above mentioned. For example, this layer may consist of potassium chloride crystals.

Applied over the crystal layer is a coating 26 of a conductive material, such as aluminum, which is of sufficient thinness to be substantially transparent to the electrons from both of the guns. The coating 26 can be deposited upon the ionic crystal layer by any process well-known in the television art.

In accordance with the invention, the layer 26 is connected to the second anode 13, so as to be at a relatively high positive potential with respect to the element 24. Likewise, the coating 8 is also connected to this second anode potential. The gun 4 is arranged to be the signal responsive gun which controls the production of the "dark trace" image on the ionic crystal screen. For this purpose the control grid 11 can be connected to any well-known source 27 of video signals, and suitably biased so as to produce a predetermined electron density in the beam from gun 4. This beam current may vary, for example, between 10 micro-amperes and 150 micro-amperes, in accordance with the video signals applied to grid 11. On the other hand, the control grid 17 of gun 5 may have a steady bias potential applied thereto from a suitable erasure control source as shown, so as to produce a beam of very much higher intensity, for example one producing a beam current of upwards of 4,000 micro-amperes. The erasure control source can be connected between the grid 18 and the source 16, and rendered effective at the desired instants of time to bias the grid 18 so that the beam from gun 5 is of the desired high intensity. We have found that with this relative proportioning of the two beam intensities, the beam from gun 4 acts in the usual way to reproduce a "dark trace" image on the ionic crystal screen, and the beam from gun 5 acts as an erasing beam for this "dark trace" image.

With the foregoing arrangement it is not necessary, in order to effect erasure of the image, to employ any separate or external heating means for the ionic crystal screen. We have found that adequate erasure of the "dark trace" image can be effected in a fraction of a second by appropriate proportioning of the intensities of the two beams and by choosing the light transparent backing sheet 24 of sufficient thinness so that while its temperature can be instantaneously raised as a result of the intense bombardment by the erasing gun 5, nevertheless its heat inertia is so low that it drops in temperature rapidly when not bombarded by the erasing beam.

The erasing action is also enhanced by reason of the fact that the electron transparent metal coating 26 is very close to the member 24, and being at high or second anode potential, there is a relatively high electrostatic potential gradient between the members 26 and 24. Since this potential gradient traverses the ionic crystal screen, it supplements the erasing action produced by the heating of the thin element 24. The potential of the coating 26 can be chosen so that in a sense it biases the ionic crystals so that when only the beam from gun 4 is acting, the crystals respond in opacity to the signal-modulated beam intensity. However, when the higher intensity beam from the erasing gun bombards the mica or glass sheet 24, it produces an enhanced potential gradient between the elements 24 and 26 of sufficient magnitude to effect erasure. In other words, the electron beam from the erasing gun 5 in striking the aluminum layer 26, releases secondary electrons, thus charging layer 26 positively and producing an increased positive field potential gradient between 26 and 24. Because of the high intensity of the erasing beam, and since the sheet 24 is "floating," the negative electrons from the erasing beam which bombard the sheet 24, will impart to it a substantial negative voltage, thus accentuating the voltage gradient between the elements 24 and 26. In other words, a suitable voltage gradient is produced between the opposite faces of the ionic crystal layer 25 by the erasing gun to effect erasure of the "dark trace" previously produced by the gun 4. In order to further accentuate the erasing action of the beam from gun 5, the surface of coating 26 facing the guns can be provided with any well-known coating of secondary electron-emissive material so that the impingement of the erasing beam on the coating 26 releases sufficient numbers of secondary electrons to raise the positive electrostatic potential of plate 26 sufficiently to exert the necessary erasing action on the ionic crystals.

The manner of using the "dark trace" tube above described, to project the images on a suitable screen, is well-known in the art. For example, a suitable steady light source 27 can be mounted on one side of the screen, and by means of a suitable optical system 28, it can be projected through the "dark trace" screen so as to illuminate the projection screen 29.

Since the gun 5 merely acts as an erasing gun, it is not necessary that it be focussed in a movable minute scanning spot on the ionic screen. For example, it may produce a beam of the above-mentioned high intensity and of sufficient cross-section to simultaneously illuminate the entire screen. In that event it is not necessary to employ the deflector plates or elements 21, 22, it being merely necessary to provide any suitable and well-known beam-blanking arrangement which blanks-off the beam from gun 5 at a predetermined high rate. For example, when the beam from gun 4 has executed one complete scanning of the ionic screen, the beam from gun 5 may be switched or "gated on" for a relatively short instant of time, so as to erase the previously-produced "dark trace" image. Since such blanking or gating control arrangements of this type are well-known in the art, detailed description thereof is not necessary herein, and any well-known electronic switch may be used for that purpose.

While in the foregoing, reference has been made to the production of opacity conditions

within the crystal layer, it will be understood that the invention is not limited to a screen wherein only two conditions of the crystals are produced, namely complete light transparency and complete opacity. Thus the signal-modulated beam can produce areas of different degrees of opacity. Without limitation thereto, it is believed that the following is an acceptable theory of the tube's operation. When an ionic crystal such as potassium chloride located in an evacuated chamber is subjected to bombardment by a cathode-ray beam, there are set up within the crystal free electrons which tend to travel in the direction of the potential gradient across the crystal. In other words, these free electrons within the crystals tend to move towards the transparent metal coating 26 which is at positive potential. Because of the presence of positive ions within the crystal lattice, a certain percentage of these free electrons are captured and form so-called color centers within the crystal body. These color centers thereupon act as light absorbers for visible light. Since the crystal lattice is in continuous thermal agitation, these so-called color centers are again broken down into positive ions and free electrons. These free electrons continue to move towards the positive coating 26. The net result is the production of an opacity center which travels through the crystal lattice towards the coating 26 and when it reaches this coating, it disappears, thus restoring the crystal to its original light transmission characteristics.

Furthermore, while the invention is not limited to any particular dimensional parameters, in one tube that was found to produce the desired results, the mica backing 24 had a thickness of .003 inch; the ionic crystal layer 25 had a thickness of 8×10^{-3} millimeters; the potential of the coating 26 was positive 10,000 volts; the current density at the coating 26 resulting from the beam of gun 4 was 10 to 150 micro-amperes; and the current density at the coating 26 from the beam of gun 5 was 1 to 6 milliamperes.

The invention is not limited to the use of two separate guns to effect the picture recording and the picture erasing. Thus the gun 4 can be used for both functions, in which event the control grid 11 can be biased at the desired instant or instants to such a potential as to produce the necessary high intensity in the beam from gun 4 for erasing purposes. Furthermore, as pointed out above, since the elemental areas of the ionic crystal screen change their light absorption properties in response to the impinging cathode-ray beam, it is not necessary that the screen be viewed by light passing through it. The screen can be viewed directly as a direct viewing screen, and if desired, the light source 27 can be located on the same side of the screen as that from which the picture is to be viewed, so that the picture can be observed by reflected light. Accordingly, in the claims, the expression "light transmitting" is used in a generic sense to cover light waves which pass through the screen from one side to the other, light waves which are reflected from the screen, and light waves which are absorbed by the screen.

The expression "image-reproducing" as employed in the claims and in the specification, is used in its generic sense to include the producing of opacity changes or light transmission or light absorption changes corresponding to electric signals representing any desired form of intelligence to be recorded or stored on the "dark

"trace" screen. The invention is not limited to the production of images of pictures, graphic or printed matter, but is capable of use in producing a stored record of any intelligence signals which are to be rapidly erased from the storing surface.

While certain specific embodiments have been described herein, it will be understood that various changes and modifications can be made therein, without departing from the spirit and scope of the invention.

What is claimed is:

1. Electro-optical translation means, comprising a cathode-ray tube having electron gun means for developing a first cathode-ray beam having its intensity modulated between predetermined limits and another unmodulated beam of much higher beam intensity than the first beam, a storage screen of the ionic crystal signal storage type located within said envelope in spaced relation to the wall thereof, said screen comprising a stratum of dark trace ionic material responsive to an impinging cathode-ray beam to develop elemental areas of corresponding variable opacity, and a sheet-like backing for said stratum, said backing having substantially its entire area out of direct heat conductive contact with the wall of said envelope.

2. Electro-optical translation means according to claim 1 in which said backing consists of a sheet having a thinness correlated with the relative intensities of said beams so as to selectively respond in temperature to bombardment by said second beam sufficiently to erase said image.

3. Electro-optical translation means according to claim 1 in which said backing consists of a thin sheet of mica.

4. Electro-optical translation means according to claim 1 in which said backing consists of a thin sheet of glass.

5. Electro-optical translation means, comprising a cathode-ray tube having a first electron gun for developing a scanning cathode-ray beam with an intensity signal-modulated between predetermined limits, a second electron gun for developing an erasing cathode-ray beam with a beam intensity much higher than the first beam, and a single "dark trace" signal storage screen cooperating with both means said screen comprising a thin sheet-like backing of light transparent electric insulating material, a coating of electron permeable conductive material on its side facing said guns, and a layer of "dark trace" controllable material sandwiched between said backing and said coating, said backing over substantially its entire area being out of direct heat conductive contact with the wall of said tube.

6. Electro-optical translation means according to claim 5, in which said coating is maintained at a high positive potential with respect to said backing, and said high intensity beam when impinging on said coating increases the potential gradient across said "dark trace" material in the same direction as the trajectory of the beam.

7. An image-producing tube of the cathode-ray controlled dark trace type, comprising, a signal-responsive dark trace recording electron gun, a dark trace erasing electron gun, a dark trace image-reproducing screen cooperating with both guns said screen comprising a thin backing sheet of light transparent electrical insulating material, an electron permeable electrode mounted between said backing and said guns, a layer of dark trace ionic crystals sandwiched between said backing and said electrode, and means to project the beam from said erasing gun on to said screen in timed relation to the projection of the beam from said recording gun to subject said crystals to an increase in temperature and to an increase of potential gradient for the purpose of restoring their opacity conditions.

8. An image-producing tube according to claim 7, in which said electron permeable window comprises a light transparent coating of aluminum on the side facing the guns and which is connected to the high potential accelerating anode of the recording gun, the opposite side of said screen being free from electric conductive coatings.

9. An image-producing tube according to claim 7, in which said electron permeable electrode is provided with a coating of secondary electron-emissive material to produce across said layer of crystals a positive potential gradient derived at least in part from said secondary electron emission, which potential gradient is in the same direction as the trajectory of the electron beams from said guns.
